UNITED STATES PATENT OFFICE

1,943,045

THERMOSTATIC GAS BURNER

Edmund J. Te Pas, Lakewood, Ohio, assignor to
The Cleveland Heater Company, Cleveland,
Ohio, a corporation of Ohio

Original application April 21, 1928, Serial No.
271,798. Divided and this application April 29,
1929. Serial No. 358,769

10 Claims. (Cl. 153—117.1)

This invention relates to gas burning appliances and in particular automatic safety fuel control systems for use in connection therewith, and is filed as a division of my copending application

5 Serial No. 271,798 filed April 21, 1928, for thermostatic valve and gas burner and which resulted on Jan. 19, 1932 in Patent No. 1,842,328.

It is the customary practice to control gas fired liquid heaters by means of a thermostatic valve

10 in contact with the liquid which is being heated. The thermostatic valve automatically controls the fuel supply to the heating burner which is used in connection with the appliance. Appliances of this type are in some cases provided

15 with a constantly burning pilot light which is independent of the operation of the main burner and which is positioned adjacent thereto for the purpose of igniting the main burner, when gas is admitted to it by means of the thermostatic valve.

20 Another arrangement which is commonly used is that of having a by-pass around the thermostatic valve, to admit at all times a small supply of gas to the burner which in this case is in operation continuously. A thermostatic valve is used to increase or decrease the flow of gas to the burner in accordance with the temperature of the liquid with which it is in contact.

25 The first named arrangement which contemplates the use of an independent pilot light, usually includes a blue flame gas burner of the atmospheric type in which a certain amount of air is premixed with the gas before combustion takes place. Burners of this type are sometimes referred to as Bunsen burners.

30 One of the difficulties encountered in the operation of the Bunsen type of burner is due to the tendency they have to flash back and burn in the mixing tube when the gas supply to the burner has been cut down below a certain limit.

35 When the burner operates in this manner it produces a dangerous amount of carbon monoxide which may lead to serious results if this poisonous gas should escape from the appliance.

40 One of the ways in which "flashing back" is prevented, is by the use of a sheet of gauze between the burner orifices and the mixing tube. This arrangement is not entirely satisfactory due to the fact that the air which is drawn into the mixing tube usually contains dust and other

45 foreign matter which in time clogs up the pores or openings in the gauze and in time entirely closes the passages between the burner orifices and the gas and air mixing tube.

50 This condition is as dangerous as the condition which the application of the gauze or screen

was intended to correct, and may result in the escape of unburned gas that might cause an explosion or a case of asphyxiation.

On account of the above characteristics of the aforementioned type of burner, the use of a 60 graduating thermostat with this type of burner has been prevented and a thermostat having a snap action valve is now generally used in this connection and for this purpose. By the use of a snap acting valve the gas burner is either 65 burning at full capacity or the gas supply is entirely shut off to the burner.

This latter arrangement does not require the use of a gauze burner and practically eliminates the tendency Bunsen burners have to flash back 70 and burn in their mixing tube. The above arrangement eliminates a great many of the difficulties encountered in the operation of the Bunsen gas burner. It necessitates however the use of a more complicated thermostatic valve 75 which materially increases the cost of the appliance with which it is used and at the same time by reason of the increased number of operating parts, is more apt to get out of order than a control which uses a simple graduating 80 thermostat.

The type of control above referred to, wherein the independent pilot light is dispensed with and the main burner is in operation at all times, considerably simplifies the control but is objectionable in that at certain times in the operation of burners of this type, the burner produces a yellow flame which is apt to cause considerable amount of soot or carbon to be deposited in the appliance.

90 Another objection to both of the above named control systems, is the possibility of extinguishment of either the pilot light or the reduced flame of the main burner. In the event of such a happening and if the thermostatic valve turns on the 95 gas supply to the main burner, there is no means present for its ignition and the full flow of unburned gas escapes from the burner. Serious accidents have occurred under such conditions where it has been attempted to relight the burner 100 when the appliance was full of unburned gas. Again under these conditions gas has escaped from the appliance with serious results.

One of the objects of my invention is to provide a thermostatically controlled gas burner that automatically cuts off the main gas supply to the burner upon extinguishment of the burner flame.

Another object of my invention is to provide a gas burner which may be controlled by a simple 105 graduating thermostat.

110

Another object of my invention is to provide an improved gas burner that efficiently operates with various kinds of gas and at various pressures.

Another object of my invention is to provide a main heating burner which does not require the use of an independent pilot light and which incorporates safety control means directly under control of the burner.

Another object of my invention is to provide a generally improved combined fuel cut-off and heating burner that contains a minimum number of parts and has a minimum number of adjustments, that is not apt to require adjustments over long periods of operation, and that is very economical in the use of the fuel used.

Another object of this invention is to provide a fuel cut-off and burner assembly which form a single operatively connected unit.

Another object of my invention is to provide a combined gas burner and automatic fuel cut-off, in which the cut-off is operative over the complete range of the burner operation, from a pilot flame to the maximum capacity flame of the burner.

A further object of this invention is to provide in a heating burner having a plurality of widely separated flame supporting orifices, a thermostatic device responsive to the heat of the burner and housed therein and adapted to cut off the fuel supply of the burner upon extinguishment of the flames of the burner.

With the above mentioned and other objects in view, the invention consists in the novel construction, arrangement and combination of parts, hereinafter described, illustrated in some of its embodiments in the accompanying drawing and particularly pointed out in the appended claims.

In the drawing exemplifying one form of my improved control; Figure 1 is a side elevational view partly in section showing my improved gas burner and thermostatic cut-off. Figure 2 is a plan view of the burner, taken on section line 2-2 Figure 1.

Referring to Figure 1, the numeral 1 designates a gas burner that is adapted to be supplied with fuel by way of the conduit 2. A thermostatic valve, having a body portion 4, is interposed between the gas supply conduit 2 and the burner 1.

The valve body 4 is provided with an inlet opening 5, adapted to be connected to the gas supply conduit 2, and an outlet opening 6, having a bushing 7 for connection with the tube 8 that communicates with the burner 1.

A valve seat 9 is formed in the valve body 4 and cooperates with the valve head 10 to control the flow of gas to the burner 1. An auxiliary outlet 11 is provided in the valve body 4 and it is adapted to receive a fitting 12 that is connected to a conduit 13. The conduit 13 is connected to the manually operable gas valve 14 which is in communication with the gas supply line 2. The valve 14 is provided for the purpose of supplying at times a limited flow of gas to the main burner 1 by way of the bypass 13 for the purpose of opening the valve controlled by the valve head 10.

When my improved cut-off is used in connection with a thermostatic regulator as shown in my application Serial No. 271,798 of which this case is a division, a limited flow of gas is supplied at all times to the burner 1 by way of the bypass 13. When the arrangement is used as a simple cut-off valve, the valve 14 is normally closed and the gas supply is entirely under control of the valve head 10 and associated mechanism.

The valve head 10 is connected to one end of

the valve stem 15. The other end of the valve stem 15 is connected by the adjusting member 16 to a strip of suitable thermostatic metal 17. The thermostatic metal 17 consists of a laminated bimetallic strip, one side of which is a metal having a high coefficient of expansion and the other side of which is a metal having a low coefficient of expansion.

This type of thermostatic metal is commonly used in temperature responsive devices and its operation is such that when subjected to changes in temperature it is warped in one direction or the other depending upon whether its temperature is raised or lowered. The strip 17 is received between a block 32 and fill-in member 33. The block 32 has an opening 18 for a tapered screw 20 to provide a means for expanding the block 32 and in this manner securely holding the upper end of the thermostatic strip 17 in the desired position.

A closure cap 21 is provided for the upper end of the tube 19. The lower end of the tube 19 is received in the burner casting 36. The lower end of the burner casting is provided with a threaded opening for the reception of the supporting tube 22. The supporting tube is in turn received in an L fitting 23 which is connected at its inlet side to the conduit 8. A compression spring 24 is compressed between the adjusting member 16 and the closure cap 25. This spring 105 is provided to assist the thermostatic metal 17 when it moves to the left as viewed in Figure 1. The member 16 is held in proper adjustment by the locknut 26 and is threadably received on one end of the rod 15.

In the open position of the valve head 10, gas is admitted to the burner 1 by way of the conduit 2 the uncovered valve seat 9 and the openings 27 which are provided in the valve body 4 for the purpose of supplying gas to the burner 1. The burner is provided in the present case with four radially arranged burner nozzles 28. The burner nozzles at their inner end have a reduction orifice or central opening 34 which becomes enlarged as at 35 just before it reaches the laterally drilled 120 inlet air openings 29.

The burner tubes 28 are partially enclosed or shielded by the wings 30 that form a part of the burner casting 36. The wings terminate in, and support deflector plates 31 that are shaped so as to deflect and direct the flames from the burner tubes in an upward direction. When the burner is operating at full capacity, the four flames directed from the spreader plates 31 merge and furnish a substantially circular wall of flame. By reason of the air inlet openings 29, when a small amount of gas is burned at the nozzles 28 they each provide a small blue flame.

The wings 30 transmit the heat produced at the ends of the nozzles 28 to the thermostat 17. By their use the valve head 10 can be maintained open by a much smaller flame than would be possible without them.

Another purpose of the side plates or wings 30 is to shield the flames of the burner nozzles 28 and to prevent them from becoming too rapidly cooled. The effect of these plates is to promote combustion and to cause the burner 1 to operate at all times with a blue flame. It has been observed that when the side plates 30 are not used, by increasing the supply of gas to the nozzles 28, the small blue flame that these burners provide when fed a limited supply of gas, changes to a yellow flame, which upon further increase in the 150

gas flow becomes a blue flame when the gas stream impinges upon the spreader plates 31.

A plausible explanation of the above behavior of the burner is as follows:

- 8 For very small gas flows sufficient air is drawn and mixed with the gas by way of the openings 29 to provide a blue flame. On increasing the supply of gas, a greater amount of gas flows through the tube 28 and the small openings 29 are not 83
10 large enough to admit a sufficient supply of air to cause the gas to burn with a blue flame. The flame by reason of its conical shape and small exposed area does not come in contact with enough air to burn with a blue flame. Upon the 83
15 further increase of the gas flow the flame impinges upon the spreader plates 31 and is spread out in a sheet which exposes a greater area of the flame to the air and assures the complete combustion of the gas with a blue flame of intense 93
20 heat.

At such times when the burner is producing a yellow flame, as would occur at certain times in its operation when the shields 30 are not used, this yellow flame would produce a certain amount 95
25 of soot or carbon that would be deposited on the heater parts, cutting down their thermal conductivity and lowering the efficiency of the heater. By reason of the shields 30, my improved gas 100
30 burner operates at all capacities with a blue flame, providing a very efficient gas burner which does not produce soot or carbon and which completely consumes the gaseous fuel used.

In starting the burner the valve 14 of the by-pass 13 is first opened and a limited flow of gas 110
35 is supplied to the burner. Shortly after ignition of this gas the burner parts become heated. This heat is conducted to the thermostatic strip 17 which moves to the left as viewed in Figure 1, urging the valve head 10 to its open position. 115
40 Gas is then supplied to the burner by way of the uncovered valve seat 9, and the by-pass controlling valve 14 is then closed.

By this construction the thermostatic strip 17, when in a heated condition, acts as a spring tending to urge the valve head 10 to its open position. When in a cooled state the thermostatic strip holds the valve head 10 against its seat, closing off the main gas supply to the burner and preventing the admission of this gas supply to the 120
50 burner until the burner is reheated in the manner described.

Thus the main burner in this device has a thermostatic valve intimately associated with it to control the flow of gas thereto. This valve provides a positive shut off of the gas supply to the main burner at such times as when it would be dangerous to admit such flow to the burner, namely, upon the extinguishment of the burner flame.

60 The coil spring 37 acts on one side of the valve head 10 and causes it to follow the movement of the rod 15 and the thermostatic element 17. The spring 37, at its end opposite to the valve head 10, is adjustably supported by an abutment 38 125
65 that is in turn carried by the adjusting screw 39. A closure cap 41 and gasket 40 prevent the escape of gas from about the screw 39.

The preceding elements provide a simple adjusting means for the valve, which is effected by 130
70 increasing or decreasing the tension of the spring 37. Thus by compressing the spring 37, the valve head engages its seat 9 when the strip 17 and burner 1 are at a higher temperature than would be necessary for the closing of the valve if less 135
75 force were exerted by the spring.

If the thermostatic metal 17 is in a heated condition, which condition exists only when the burner 1 is in operation, the valve head 10 is in an open position and gas is admitted to the burner 1. Should the burner be extinguished for any reason, the thermostatic metal 17 cools and at the same time shifts and maintains the valve head 10 in contact with its seat 9.

83
85 From the foregoing it is apparent that the gas supply of my improved burner is at all times responsive to, and under control of the heat of the burner. The heat of the burner is necessary for the opening of the valve and in the absence of such heat or upon the extinguishment of the burner, the valve which controls the main gas supply to the burner is in a normally and permanently closed position.

93
95 By this arrangement a novel safety means is provided that serves to prevent the escape of unburned gas from the burner, eliminating the hazardous condition which would arise if the burner flame had been accidentally extinguished.

100 Another advantage of the construction illustrated is that all the operating elements of the system are intimately connected with each other and function as a single unit. This arrangement greatly simplifies the construction of the device and facilitates its installation on the appliance.

105 My improved burner and safety control could be used in connection with other gas burning appliances where the operation of the burner is automatically controlled by the temperature of the medium which the burner is adapted to heat.

110 Furthermore, it is to be understood that the particular forms of apparatus shown and described, and the particular procedure set forth, are presented for purposes of explanation and illustration and that various modifications of said apparatus and procedure can be made without departing from my invention as defined in the 115
115 appended claims.

I claim:

120 1. In a variable capacity main heating gas burner, the combination of a burner head, mixer tubes carried by the burner head for supporting a plurality of flames at points radially spaced a substantial distance from the center of said burner head, means out of the path of the burner flames and adjacent to the ends of said mixer tubes for conducting heat from the flames supported thereto to the central portion of the burner head, and thermostatic means responsive to the temperature of the central portion of the burner head for cutting off the supply of gas to the burner upon its extinguishment.

125 2. In a variable capacity main heating gas burner, the combination of a burner head, mixer tubes carried by the burner head for supporting a plurality of flames at points radially spaced a substantial distance from said burner head, means adjacent to the ends of the mixer tubes and located alongside the gas stream issuing therefrom and out of contact therewith for conducting heat radiated from the flames supported at the ends of said mixer tubes to the central portion of the burner head, and thermostatic means responsive to the temperature of the central portion of the burner head for cutting off the supply of gas to the burner upon its extinguishment.

130 3. In a gas burner, the combination of a burner head, mixer tubes carried by the burner head for supporting a plurality of flames at points radially spaced in the center of said burner head, means adjacent to the ends of the mixer tubes for shield- 135
140
145
150

ing the flames supported thereat, for directing a supply of secondary air thereto and for conducting heat from such flames to the central portion of the burner head, and thermostatic means responsive to the temperature of the central portion of the burner head for controlling the supply of gas thereto.

4. In a gas burner, the combination of a burner head, mixer tubes carried by the burner head for supporting a plurality of flames at points radially spaced from the center of said burner head, means adjacent to the ends of said mixer tubes positioned alongside of the gas stream issuing therefrom for shielding such flames, for directing a supply of secondary air thereto and for the purpose of conducting heat therefrom to the central portion of the burner head, and thermostatic means responsive to the temperature of the central portion of the burner head for controlling the supply of gas thereto.

5. In a variable capacity main heating gas burner, the combination of a burner head, mixer tubes carried by the burner head for supporting a plurality of flames at points spaced a substantial distance from the center thereof, means adjacent to the ends of the mixer tubes out of the path of the gas stream issuing therefrom for conducting heat radiated from the burner flames to the central portion of the burner head, a gas supply conduit communicating with the central portion of the burner head, thermostatic means in said supply conduit responsive to the temperature of the heat conducted thereto from the central portion of said burner head, and valve means actuated by said thermostatic means for cutting off the gas supply of said burner upon the extinguishment thereof.

6. In a safety fuel control for a gas burner responsive in its operation to the heat produced by the gas burner, the combination with a burner head, of a series of gas and air mixing tubes extending radially from said head, a radially projecting member arranged below each of said tubes, each member having a surface extending across the path of the gaseous mixture issuing from the adjacent tube for absorbing heat when the burner is operating at full capacity and having a vertically disposed wall positioned on each side of the path of the gaseous mixture issuing from said tubes for absorbing heat when the burner is operating at low capacity, and a thermostatically operated fuel control device arranged to have heat conducted to it by said members and to shut off the burner gas supply upon the extinguishment of the burner flames.

7. In a safety fuel control for a gas burner responsive in its operation to the heat produced by the gas burner, the combination with a central gas supply conduit, of a burner head mounted thereon, a series of mixing tubes extending radially from said head in a horizontal plane, and a member connected to said burner head below each of said tubes having vertically dis-

posed pairs of spaced walls for absorbing heat when said burner is operating at low capacity and terminating in an imperforate portion crossing the path of the gas stream issuing from said tube for absorbing heat when said burner is operating at full capacity, said crossing portions being spaced from said tubes and being gradually curved from the horizontal to the vertical, and a thermostatically operated fuel control device arranged to have heat conducted to it by said members and to shut off the burner gas supply upon the extinguishment of the burner flames.

8. In a safety fuel control for a gas burner responsive in its operation to the heat produced by the gas burner, the combination of flame supporting gas and air mixing tubes and cooperating heat absorbing means for deflecting and spreading the flames issuing from said mixing tubes when gas is supplied thereto at a pressure greater than a predetermined pressure, and heat absorbing means to shield and direct a supply of air to the flames issuing from said tubes for the purpose of maintaining such flames substantially blue flame in character when the burner is operated at gas pressures below the stated predetermined pressure, and a thermostatically operated fuel control device arranged to have heat conducted to it by said means and operable to shut off the burner gas supply upon the extinguishment of the burner flames.

9. A safety gas burner for heating purposes adapted for the efficient utilization and combustion of a gaseous fuel under varying or fluctuating gas pressures, comprising fuel supplying and distributing means providing a plurality of flame supporting ports, a safety fuel control device for said burner operable to cut off the burner gas supply upon the extinguishment of the burner, and means located out of the path of the burner flames for absorbing heat radiated by the burner flames and conducting it to said device when said burner is operating under reduced gas pressures, and other means located in the path of each of the burner flames when gas is supplied to them at relatively high pressures for supplying heat to said device.

10. A safety gas burner for heating purposes adapted for the efficient utilization and combustion of a gaseous fuel under varying or fluctuating gas pressures, comprising fuel supplying and distributing means providing a plurality of flame supporting ports, a safety fuel control device for said burner operable to cut off the burner gas supply upon the extinguishment of the burner, and separate means cooperating with each of the burner flames for supplying sufficient heat to said device to maintain it in fuel supplying position between the minimum and maximum gas pressures at which said burner is arranged to operate.

EDMUND J. TE PAS.
